CLAIM(51) LOC (7) Cl. ..... **14-02**The ornamental design for an interface unit for computer, as
shown and described.(52) U.S. Cl. ..... **D14/433; D14/242****DESCRIPTION**(58) **Field of Search** D14/432-439,
D14/242, 191; 439/610, 620; 361/681-686FIG. 1 is a front elevational view of an interface unit for
computer showing my design;(56) **References Cited**

FIG. 2 is a rear elevational view thereof;

U.S. PATENT DOCUMENTS

FIG. 3 is a left side elevational view thereof;

D331,395 S	*	12/1992	Lou	.....	D14/433
D340,059 S	*	10/1993	Wetzel et al.	.....	D14/433
D345,980 S		4/1994	Scheid et al.	.....	D14/191
D361,332 S	*	8/1995	Scheid et al.	.....	D14/191
D366,047 S	*	1/1996	Rak et al.	.....	D14/242

FIG. 4 is a right side elevational view thereof;

FOREIGN PATENT DOCUMENTS

FIG. 5 is a top plan view thereof;

GB	2085406	11/1999
JP	872595	7/1993
JP	889840	2/1994
JP	890760	2/1994
JP	1009939	5/1998
JP	1085948	9/2000

FIG. 6 is a bottom plan view thereof;

FIG. 7 is an enlarged left side elevational view thereof;

FIG. 8 is a perspective view thereof, and,

FIG. 9 is a partially enlarged perspective view taken along
the line 9—9 of FIG. 1.Portions in broken lines are for illustrative purpose only and
form no part of claimed design.**1 Claim, 4 Drawing Sheets**FIG.1

FIG.2

FIG.3

FIG. 4

FIG. 5

FIG. 6

FIG. 7

FIG. 8

FIG. 9
